MULTIOFFICE TELEPHONE SYSTEM

Application filed March 31, 1932. Serial No. 602,124.

This invention relates to telephone systems in general, particularly to multi-office telephone systems which include satellite or sub-offices and in which connections are completed through the medium of automatic switches. The invention has for its object the provision of new and improved circuits and apparatus for interconnecting the various offices in such systems to provide reliable and efficient local, toll, and auxiliary services.

In systems of the above type, the toll and auxiliary service switchboards are usually located at one of the main offices, and special service calls from all offices of the system are extended thereto. The special service traffic may be routed over the same inter-office trunks as the regular interoffice traffic according to the arrangement shown in the co-pending application of V. S. Tharp, Serial No. 469,530, filed July 21, 1930, or a separate group of trunks may be provided for each class of traffic. In either case, the trunks over which the special service traffic is handled will require provisions for the so-called C. I. R. toll service as a large percentage of the toll traffic is handled on this basis in present-day practice.

If the regular interoffice traffic is heavy and the trunk groups are accordingly large, it is often more economical to provide a separate trunk group for the special service traffic than to equip the regular trunks for this service. In case a satellite or sub-office is involved, the trunking arrangement must take into consideration the maintenance of uniform numbering throughout the system. Further, there must be no interference between the special service code numbers and the numbers assigned to subscribers' stations even though both numbers utilize certain digits in common.

The present invention provides a simple and efficient trunking organization for use under the above conditions. The trunking layout itself constitutes one feature of the invention; and an improved selector repeater, which makes this layout possible, constitutes another feature. These features, and others not specifically mentioned, will be described hereinafter in connection with the detailed

description of the system embodying the invention, which is shown in the accompanying drawings, of which Fig. 1 shows diagrammatically a part of the trunking layout of a main office and an interconnected sub-office. Fig. 2 shows circuits of equipment located at the sub-office.

Referring now to Fig. 1, the equipment located to the left of the broken line is located in the sub-office, and that located to the right of the broken line is located in the main office. The sub-office subscribers' lines terminate in lineswitches LS, which have access to switching-selector repeaters SSR. The selector repeaters have access by way of their banks to trunks extending to local third selectors S and over the first level of their banks to trunks T1, which terminate in incoming special second selectors at the main office. Associated with each selector repeater is the usual secondary lineswitch SLS which has access to trunks T extending to incoming selectors at the main office. The sub-office selectors, such as S, have access to local connectors C, and these in turn have access to the sub-office subscribers' lines. It will be understood, of course, that trunking equipment is provided for incoming calls from the main office, but since this forms no part of the invention it has been omitted in the drawings.

In the main office, subscribers' lines terminate in lineswitches LS1 which have access to first selectors 1S. As previously stated, the trunks from the sub-office terminate in incoming selectors 1S. The banks of the incoming selectors are multiplied with the banks of the main office first selectors on all levels except the first. The first level of the banks of the incoming selectors is unequipped and the corresponding level of the main office first selectors terminates in trunks extending to the special second selectors S2S. The special service trunks from the first level of the selector repeater at the sub-office terminate in incoming second selectors 12S at the main office. The banks of these selectors are multiplied on all levels with the banks of the main office special second selectors. Further, the banks of all of these special selectors are

55

multiplied on all levels except the first with the banks of the local first selectors and incoming selectors of the main office. The special selectors have access by way of the first level to trunks extending to special third selectors S3S and these in turn have access over various levels to the special service trunks. The combined line and recording trunk CLR, accessible in the tenth level of 10 the special third selectors, has been shown by way of illustration. The first selectors and incoming selectors on the various multiplied levels have access to local second selectors 2S, and these in turn to local third selectors 3S.

15 The third selectors have access to the various groups of connectors, including the group represented by connector C, which in turn have access to the main office subscribers' lines.

20 The system shown is of the five-digit or 100,000-line type. A total of two thousand numbers have been assigned for sub-office subscribers in the thirty-three- and thirty-four-thousand groups, respectively. All other numbers including the 31,000, 32,000, and 35,000 to 30,000 groups are allocated to the main office. The code numbers assigned to special services all start with the digits 11, the code 110, for example, being assigned to 30 CLR toll service.

Referring now to Fig. 2, subscriber's line A and lineswitch LS may be of the usual type in use in automatic telephone systems. Selector repeater SSR is the usual type of 35 Strowger switch provided with a fourth wiper for switching purposes in addition to the usual line and test wipers. Associated with the selector repeater is a secondary lineswitch SLS which has access to the trunks, 40 such as T, extending to the main office. The banks of the selector repeater, part of which are shown in the drawings, consist of a 200-contact line bank and a 200-contact test bank. The upper contacts of the first set in each 45 level of the test banks are wired in a manner to permit the switch to select the proper route over which the call is to be extended. In the line bank, the first level is assigned to trunks T1, which extend to incoming special 50 second selectors at the main office, and the third and fourth levels are assigned to trunks extending to local third selectors in the sub-office. The remaining levels of this bank are unequipped.

55 With the foregoing brief description in mind, the operation of the selector repeater and associated equipment in various calls will now be described in detail. It may be assumed that the subscriber at substation A has 60 initiated a call and that lineswitch LS has extended the calling line to the trunk comprising conductors 12-14, which terminates in switching-selector repeater SSR. Line relay 4 operates over a circuit which includes 65 trunk conductors 12 and 14, contacts 15 and

21, contacts 24 and 30, and the upper and lower windings of the relay, which are connected to ground and battery, respectively. Relay 4 completes a circuit for relay 5 at contacts 32, and at contacts 33 closes a starting circuit for the secondary lineswitch which will be described subsequently. Relay 5 operates, prepares the impulsing circuit at contacts 35, connects ground to release trunk conductor 13 and to the lower winding of polarized relay 7 at contacts 36, and at contacts 37 completes a circuit for relay 2 and applies ground to holding conductor 68 which extends to the secondary lineswitch. Relay 2 operates, prepares the metering circuit at contacts 22, and completes a holding circuit for itself at contacts 23. Polarized relay 7 does not operate at this time.

Referring now to the secondary lineswitch, relay 73 operates over the circuit prepared by relay 4, which may be traced from ground, winding of relay 73, contacts 81, conductor 67, contacts 33, upper winding of polarized relay 7, resistance 71, conductor 66, contacts 75, resistance 95, and contacts 94, to battery. This circuit is completed only in case an idle outgoing trunk is available, which is assumed to be the case at this time. Relay 73, accordingly, operates and completes a test circuit at contacts 84. In case the wipers are standing on the contacts associated with a trunk which is engaged in a connection, wiper 88 finds ground on the test contacts of the trunk, and this ground by way of contacts 77, 84, and 86 energizes stepping magnet SM of the lineswitch. Relay 72 is shunted by the ground on the test contact and does not operate. The stepping magnet on operating opens its own circuit at contacts 86, and on deenergizing advances the wipers one step to the next set 105 of contacts. This operation is repeated until an idle trunk is found, for example the trunk T, whose idle condition is indicated by the absence of ground on the test contact. Relay 72, accordingly, operates from ground on the 110 holding conductor 68, contacts 86, winding of the stepping magnet, to battery. The stepping magnet does not operate due to the high resistance of the relay. Relay 72 opens the 115 test circuit at contacts 77, and completes a holding circuit for relay 73 at contacts 78. The initial operating circuit of relay 73 is opened at contacts 75 and 81, and line conductors 66 and 67 are connected through by 120 way of contacts 76 and 80, contacts 82 and 85, and wipers 87 and 90, to the conductors of the seized trunk. Relay 72 also completes a circuit for trunk relay 74 by way of contacts 79 and wiper 89. Relay 74 on operating applies ground to the test contact of the trunk at contacts 92, and at contacts 91 closes a point in the chain circuit for relay 93.

If all outgoing trunks are engaged at the time the call is initiated, all of the trunk relays corresponding to relay 74 will be oper- 130

ated and the chain circuit of relay 93 will be completed. Relay 93 will be energized and battery will be removed from the starting circuit of all idle secondary lineswitches by the opening of contacts 94. Accordingly, a call initiated under these conditions will not be extended to the main office. In this case, however, it is desirable to permit the subscriber to dial sufficient digits to indicate the zone of the call. The calling subscriber will, therefore, be given a dial tone, which will notify him that the apparatus is in condition to receive the dial impulses. The circuit for the tone extends over contacts 51 and 43, conductor 69, contacts 83 and 76, conductor 66, contacts 38, through the upper talking condenser of the selector repeater, to the upper line conductor of the calling line. If the subscriber dials the number of a station connected to the sub-exchange, the main office branch extending to the secondary lineswitch will be disconnected and the connection will be completed over the wipers of the selector repeater, as will be explained subsequently. However, if the number dialled indicates a main office call the wipers of the selector repeater will be held in an off-normal position, and relay 8 of the selector repeater will substitute busy tone for the dial tone by opening contacts 43 and closing contacts 44. The subscriber is then expected to release the connection by hanging up his receiver.

Before proceeding with the description, it will be well to consider the various combinations of numbers which the subscriber may dial. If the subscriber is calling another subscriber in the sub-office, the first digit will, of course, be the digit 3, which is characteristic of all sub-office numbers. The second digit will be either a 3 or a 4, the latter of which is also the first digit of certain main office numbers. If the call is for a subscriber in the main office, the first digit may be 3, 4, or any digit above this, in which case the selector repeater will cease to function and the call will be extended over the seized main office trunk. If the call is for the special service operator, the first digit will be 1, and in this case the connection will be switched over the wipers of the selector repeater, and the service connection at the main exchange will be released immediately.

To resume the description, it will be assumed that the calling subscriber wishes to extend a connection to another sub-office subscriber whose number is in the 33,000 series. The branch connection to the main office having been established over trunk T as previously described and the selector repeater prepared for the receipt of impulses, we have the following operation upon the receipt of the first series of impulses: Relay 4 on de-energizing in response to each impulse of the calling device completes a circuit over contacts 31, 17, 35, and 56 for vertical mag-

net VM, and the latter raises the switch wipers step by step to the third level. Relay 6, which is connected in parallel with the vertical magnet, operates in response to the first impulse of the series, and, due to its slow-releasing characteristics, remains operated throughout the series of impulses. The upper winding of relay 7 and resistance 71 are short circuited by the closure of contacts 39 to improve the transmission of impulses over the trunk to the main office. The impulses are repeated by relay 4 at contacts 33, and the incoming selector at the main office is raised to the third level simultaneously with the operation of the selector repeater. Relay 8 operates upon the first vertical step of the wipers of the selector repeater due to the closure of vertical off-normal contacts 96. Relay 9 now operates over a circuit which may be traced from ground at contacts 37, contacts 40, 98, 46, and 59, winding of the relay, to battery. Relay 9 on operating prepares the rotary magnet circuit at contacts 49, at contacts 48 completes a holding circuit for itself which may be traced from battery, winding of the relay, contacts 59, 46, 98, 61, 48, 36, and 26, to ground. Shortly after the last impulse of the series, relay 6 restores and completes a circuit by way of contacts 41 and 49 for rotary magnet RM. The rotary magnet energizes and steps the wipers in on the first set of contacts of the banks of the called level and opens the holding circuit of relay 9 at contacts 61. Relay 9 restores and opens the rotary magnet circuit at contacts 49. As soon as the wipers engage the bank contacts, a circuit is completed from ground, contacts 26, 36, and 54, upper contact of the test bank, wiper 62, winding of relay 11, to battery. Relay 11 operates, opens the vertical magnet circuit at contacts 56, completes a circuit for the release magnet at contacts 57, closes the circuit for the upper winding of relay 10 at contacts 58, which circuit is of no utility in the present instance, opens the circuit of relay 9 at contacts 59, and opens the circuit of the test wiper 63 at contacts 60. It will be noted that the closure of contacts 58 completes a circuit by way of the upper winding of relay 10, contacts 52, winding of release magnet, to battery; and that a parallel circuit is completed over contacts 45 and 57. Relay 10 accordingly is short circuited and does not operate, but the release magnet does operate and restores the wipers of the switch to normal. A locking circuit is completed for the release magnet at contacts 50 to insure its continued energization after the wipers leave the bank and start to restore vertically. Upon the switch wipers reaching normal position, relay 8 opens the circuit of the release magnet at contacts 45. The opening of these contacts also removes the short circuit from the upper winding of relay 10,

and this relay now operates in series with the release magnet and completes a locking circuit for itself at contacts 53. The release magnet, however, is not able to remain energized in series with the winding of relay 10 and restores after a slight delay, opening the circuit of relay 11 at contacts 50. Relay 10 in addition to completing its locking circuit disconnects its upper winding from in series with the release magnet by opening contacts 52, opens the dial tone circuit at contacts 51, and prepares various other circuits which will be described in more detail in later paragraphs.

15 The subscriber now dials the second digit of the called number, which is also the digit 3, and the wipers of the selector repeater are again raised to the third level and stepped in on the first set of contacts. The impulses 20 are repeated over the trunk to the main office as in the previous case and serve to operate a second selector to which the incoming selector has extended the connection responsive to the first digit dialled. Since relay 10 is 25 operated, wiper 62 will not find ground on the upper test contacts and consequently relay 11 is not operated. The selector now proceeds to test for an idle trunk in the called level. Assuming that the first trunk in the 30 level is engaged, wiper 63 will find ground on the lower test contact, which ground by way of contacts 60, 19, 55, 61, 98, 46, and 59 will operate relay 9. Relay 9 completes the 35 rotary magnet circuit at contacts 49 and the wipers are accordingly advanced another step. Subsequent trunks are tested in the same manner until an idle trunk is found which is characterized by the absence of ground from the test contact. Relay 1 now 40 operates from ground by way of contacts 26 and 36, winding of the relay, contacts 55, 61, 98, 46, and 59, winding of relay 9, to battery. Relay 9 does not operate due to the high 45 resistance of relay 1. Relay 1 disconnects the incoming trunk conductors 12 and 14 from the line relay of the selector repeater at contacts 15 and 21 and extends them by way of contacts 16 and 20 and wipers 64 and 65 to the local trunk extending to the local third 50 selector. The line relay of the succeeding switch operates in the usual manner and ground is returned on the release trunk conductor which is switched over at contacts 18 to the upper terminal of relay 1. This 55 ground holds relay 1 and the switching relay of the preceding line switch in operated position. Relays 4 and 5 restore, the former opening the loop circuit originally extended over the trunk to the main office, thereby 60 releasing the switches in the main office. Ground is removed from conductor 68 upon the release of relay 5, thereby permitting relays 72 and 73 of the lineswitch to restore to normal and release the main office trunk. 65 Further impulses serve to operate the suc-

ceeding local selector and connector in the usual manner and extend the call to the called subscriber.

In case the second digit of the called number is the digit 4, the operations will be the same as those for the digit 3, since in this case the ground connection to the upper test terminal of the first contact set in this level is opened at contacts 54. It will thus appear from the foregoing explanation that the operations involved in setting up a connection of the type described is substantially the same as for the ordinary switching-selector repeater.

Calls from the sub-office to main office stations, such as station A3, involve the calling of a number whose first digit is the same as the first digit of the sub-office subscriber's numbers and whose second digit corresponds to the first and second digits of special-service code numbers. The operation of the selector-repeater in response to the first digit is exactly the same as previously described for a local call. In response to the second digit, i. e., the digit 1, the wipers of the switch are raised to the first level and rotated to the first set of contacts in this level as before. Since relay 10 was operated in response to the first digit, wiper 62 will find ground on the upper test contact by way of contacts 53, 36, and 26, and relay 11 will accordingly operate. The closure of the circuit for the upper winding of relay 10 is without effect, as this relay is now held operated over its lower winding, and the circuit of the release magnet is open at contacts 52. Relay 11, however, disconnects the vertical magnet at contacts 56 and opens the test wiper circuit at contacts 60 and the selector repeater remains at rest upon the first set of contacts of the first level throughout the rest of the call. The wipers standing on these bank contacts do not interfere with the extension of calls over the trunk as the line wipers are disconnected at contacts 16 and 20 and the test wiper is disconnected at contacts 60. Subsequent impulses are repeated over the trunk as before and serve to operate the remainder of the switch train at the main office and extend the connection to the called line therein.

When the called subscriber responds, the connector reverses battery over the trunk in the usual manner and relay 7 of the selector repeater operates due to its two windings assisting each other. Relay 7 connects relay 3 in series across the outgoing trunk by closing contacts 42 and opening contacts 100. Relay 3 operates, completes another point in the metering circuit at contacts 27, opens the circuit of relay 2 at contacts 28 and reverses the connection of the calling line to the line relay of the selector repeater by opening contacts 24 and 30 and closing contacts 25 and 29. Metering or booster battery is applied to the release

trunk of the calling line over the lead MB, resistance R, contacts 23, 27, 36, and conductor 13. This application of metering current is only momentary as relay 2 restores after 5 a short interval and opens the metering circuit at contacts 22. The opening of contacts 23 prevents the reoperation of relay 2, and consequently prevents the reoperation of the meter during the remainder of the 10 call.

When the calling subscriber hangs up at the termination of the call, relay 4 releases, followed by the release of relay 5. A circuit is closed for the release magnet via contacts 15 31, 17, 34, 101, and the magnet operates to restore the switch wipers to normal position. Relay 8 releases following the restoration of the wipers, and the remainder of the relays 20 deenergize and release due to the opening of contacts 36 and 37. The opening of the loop to the main office permits the switches therein to release in the usual way.

A call from a sub-office subscriber to a main office subscriber whose number begins with some other digit than the digit 3 will now be considered. The sub-office equipment operates as in the previously described connection responsive to the initiation of the call. 25 Assuming that the number called begins with digit 5, and the calling subscriber dials this digit, the wipers of the selector repeater are raised to the fifth level and step in on the first set of contacts in the same manner described for previous calls. The series of impulses is 30 also repeated over the trunk to the main office and operates the incoming selector in that office to the fifth level, in which an idle trunk to a second selector is selected. Upon engaging the first set of contacts, test wipers 62 of 35 the selector repeater finds ground through resistance R1. Relay 11 operates in a circuit including the test wiper and the resistance and completes the various circuits described for previous connections. It will be recalled 40 that relay 11 upon operating connects the release magnet of the selector repeater in parallel with itself and also completes a circuit for the release magnet and the upper winding of relay 10 in series. In the present connection 45 the release magnet does not operate at this time due to the inclusion of resistance R1 in the circuit. This resistance also is of such value that relay 10 is enabled to operate in series with the release magnet and lock up over 50 its lower winding. Relay 10, of course, opens the release magnet circuit at contacts 52 and completes various other circuits as before. The subscriber then dials the remaining 55 digits of the called number which are repeated over the trunk to the main office in the usual manner but do not operate the selector repeater further. The selector repeater accordingly remains, throughout the 60 call, in the position to which it was operated by the first digit.

When the calling subscriber hangs up, relays 4 and 5 release and permit the selector repeater to release in the usual manner. The opening of the loop circuit over the trunk to the main office permits the main office switches 70 to restore as usual.

The operations involved in establishing a special service connection will now be described. Assuming that the subscriber at 75 substation A is calling and that lineswitch LS has operated to extend the calling line to selector repeater SSR as in the previous case, the selector repeater is prepared for operation and the branch connection is extended to the main office as described in previous 80 connections. The subscriber then dials the first digit, that is, the digit 1, and line relay 4 of the selector repeater transmits a single impulse to the vertical magnet of the switch, which raises the wipers opposite the first 85 level of bank contacts. Relay 6 operates in parallel with the vertical magnet and, upon the operation of the off-normal relay 8, completes a circuit for stepping relay 9. Relay 6 releases shortly after the impulse and completes the rotary magnet circuit which is prepared by relay 9, and the magnet steps the wipers in on the first set of bank contacts. On operating the selector repeater to the first 90 level, normal post springs NPS operate to close contacts 99, thereby completing a circuit for test wiper 63, independent of contacts 55 of relay 10. This prepares the selector repeater for testing the trunk in the first 95 level without first requiring the operation of relay 10 as was the case on calls to local subscribers in the sub-office. The trunks are accordingly tested in the usual manner and when an idle one is found the absence of 100 ground on the contact engaged by wiper 63 permits relay 1 to operate in series with relay 9. The calling line accordingly is disconnected from the line relay of the selector repeater at contacts 15 and 21, and at 105 contacts 16 and 20 is connected through wipers 64 and 65 to the talking conductors of the trunk extending to the main office from the first level of the selector repeater banks. As 110 previously stated, these trunks terminate in incoming special second selectors at the main office whose banks are multiplied with the local special second selectors at that office. The branch connection to the main office is released following the operation of relay 1 and the consequent release of relays 4 and 5. The subscriber then dials the second digit of 115 the special service code, again the digit 1, and the incoming special second selector is operated to the first level in which a trunk to a special third selector is selected. The third digit, which may be the digit 0 for example, in case the call is for the toll recording-completing operator, will operate the special third selector to the tenth level, and an 120 idle trunk in that level will be selected. The 125 130

operator answers the call and extends the toll connection in the usual manner, and at the termination thereof releases the connection by withdrawing the plug at the answering board of the jack.

What is claimed is:

1. In a telephone system, a main office and a sub-office, two groups of trunks connecting the offices, local trunks in the sub-office, a selector repeater in the sub-office for extending local or outgoing calls, means in the selector repeater for preliminarily routing all calls to the main office via an idle trunk in one of said groups, means responsive to the receipt of an impulse series of a particular value for switching the call from the trunk in said one group to an idle trunk in the other of said groups, and means responsive to the receipt of a plurality of impulse series of particular values for switching the call from the trunk in said one group to an idle one of the local trunks.

2. In a telephone system, a main office and a sub-office, two groups of trunks connecting the offices, local trunks in the sub-office, a selector repeater equipped with a set of wipers, means associated with the selector repeater for preliminarily routing all calls to the main office via an idle trunk in one of said groups and independent of said wipers, and means for operating the selector repeater to switch a call to either an idle trunk in the other of said groups or to an idle one of the local trunks via said wipers.

3. In a telephone system, a main office and a sub-office, two groups of trunks connecting the offices, local trunks in the sub-office, a selector repeater equipped with a set of wipers, means associated with the selector repeater for preliminarily routing all calls to the main office via an idle trunk in one of said groups and independent of said wipers, means for transmitting digit impulses to the selector repeater to determine the ultimate routing of a call, means in the selector repeater responsive to the receipt of a digit of a particular value for releasing the trunk in said one group and for extending the call to the main office via said wipers and an idle trunk in the other of said groups, and means in the selector repeater responsive to the receipt of a plurality of digits of particular values for releasing the trunk in said one group and for extending the call via said wipers to an idle local trunk.

4. In a telephone system, a main office and a sub-office, subscribers' lines terminating in each office, an operator's switchboard in the main office, two groups of trunks connecting the offices, a selector repeater at the sub-office, means responsive to the initiation of a call by a sub-office subscriber for connecting the subscriber's line to the selector repeater, means associated with the selector repeater for preliminarily extending a connection to

the main office, subscriber-controlled means for transmitting digit impulses to determine the ultimate routing of the call, means responsive to digits indicating a call to a main office subscriber for disabling the selector repeater and for completing the connection over the trunk engaged initially, means responsive to digits indicating a call to a sub-office subscriber for releasing the initially engaged trunk and for completing the connection through the selector repeater, and means responsive to digits indicating a call to said switchboard for releasing the initially engaged trunk and for completing the connection through the selector repeater and over an idle trunk in the other of said groups.

5. In a telephone system, an automatic switch having wipers, a contact bank comprising a plurality of levels accessible to said wipers, outlets terminating in the contacts of certain levels, an auxiliary switch associated with said first switch, other outlets accessible to said auxiliary switch, means for seizing said first switch and for transmitting thereto a plurality of series of impulses in accordance with the digits of a called number, means responsive to the seizure of the switch for operating the auxiliary switch to extend a connection over an idle outlet accessible thereto, means responsive to the first series of impulses for raising the wipers of the first switch to a level corresponding to the digit represented by the impulse series and for simultaneously repeating the impulses over the connection established via said auxiliary switch, means responsive to the initial operation of the switch wipers to a certain level for restoring the wipers to normal and for rendering them reoperable responsive to the next series of impulses received, means responsive to the initial operation of the switch wipers to a different level for maintaining the same in operated position while a connection is completed via the auxiliary switch, and means responsive to the initial operation of the switch wipers to a still different level for causing the wipers to be moved over the level in search of an idle outlet accessible therein and for releasing the connection established over the auxiliary switch.

6. In a telephone system, a two-motion switch, primary and secondary magnets for the switch, a stepping relay for controlling the secondary magnet, a second relay, means for operating said primary magnet to set the switch, means responsive to a particular setting of the switch for operating said second relay to complete a circuit for said stepping relay, and means responsive to a different setting of the switch for completing a circuit for said stepping relay independent of said second relay.

7. In a telephone system, a two-motion switch, primary and secondary magnets for the switch, a stepping relay for controlling

70

the secondary magnet, a second relay, a wiper for the switch, means for operating said primary magnet to set the switch, means responsive to a particular setting of the switch for operating said second relay to connect the stepping relay to said wiper, and means responsive to a different setting of the switch for connecting the stepping relay to said wiper independent of said second relay.

8. In a telephone system, a two-motion switch, primary and secondary magnets for the switch, a relay for controlling said secondary magnet, a second relay, a wiper for the switch, means for operating the primary magnet to set the switch, means responsive to a particular setting of the switch for operating said second relay and for releasing the switch, contacts operated by said second relay for connecting the first relay to said wiper, and means responsive to a different setting of the switch for connecting the first relay to said wiper without releasing the switch.

9. In a telephone system, a two-motion switch, primary and secondary magnets for the switch, a test wiper for the switch, a stepping relay and a control relay, means for operating the primary magnet to set the switch, means responsive to a particular setting of the switch for operating said control relay and for releasing the switch, contacts on said control relay for rendering said stepping relay effective to control said secondary magnet after the primary magnet is reoperated to reset the switch, and contacts closed mechanically responsive to a particular initial setting of the switch for short circuiting the contacts of said control relay whereby said stepping relay is rendered effective to control the secondary magnet without releasing and resetting the switch.

10. In a telephone system, a selector repeater, wipers for the selector repeater, contacts disposed in a plurality of rows accessible to said wipers, circuit connections for normally connecting switching potential to contacts in certain of said rows, other circuit connections normally ineffective for connecting switching potential to a contact in a different one of said rows, means for operating the selector repeater to set the wipers on contacts in one of said certain rows, and means responsive to said wipers engaging a contact therein for rendering said first circuit connections ineffective and for rendering said other circuit connections effective.

11. In a telephone system, a selector repeater, wipers for the selector repeater adapted to engage contacts in a plurality of levels, circuit connections to contacts in certain of said levels normally marking such levels as switching levels, other circuit connections to a contact in a different level for marking that level as a switching level, and means responsive to a preliminary setting of the selector repeater wipers to a contact in one of said switching

levels for rendering said other circuit connections effective.

12. In a telephone system, a selector repeater, a wiper for the selector repeater, two contacts accessible to said wiper, conductors extending from said contacts to the selector repeater, means in the selector repeater for connecting a potential to one of said conductors when the selector repeater is taken into use, means for operating the selector repeater to set its wiper on the contact to which said one conductor is connected, and means responsive to the wiper engaging said contact for disconnecting the potential from said one conductor and for connecting it to the other conductor.

In witness whereof, I hereunto subscribe my name this 25th day of March, 1932.

OSCAR C. LEVY.
